UNITED STATES PATENT OFFICE.

MICHAEL REDLINGER, OF FREEPORT, ILLINOIS, ASSIGNOR TO THE ARCADE MANUFACTURING COMPANY, OF SAME PLACE.

DESIGN FOR A FRAME FOR CORK-EXTRACTORS.

SPECIFICATION forming part of Design No. 25,607, dated June 9, 1896.

Application filed May 21, 1894. Serial No. 512,015. Term of patent 7 years.

To all whom it may concern:

Be it known that I, MICHAEL REDLINGER, a citizen of the United States of America, residing at Freeport, in the county of Stephenson and State of Illinois, have invented and produced a new and original Design for a Frame for a Cork-Extractor, of which the following is a specification, reference being had to the accompanying drawing, which is a side elevation of a frame for a cork-extractor made in accordance with my design.

In the drawing, A is one of the two approximately similar parts of a hollow shell formed with two horizontal lugs B B', the lug B extending from the shell about midway between its ends and the lug B' near its bottom. The

upper portion *a* of the margin of the shell is approximately an arc having at its extremities the converging lines *a' a'*, which merge at their lower ends into approximately parallel lines *a'' a''*, preferably curving outward slightly at their lower ends. These marginal lines determine the outline of my design, and this outline I consider the essential feature of my design. 25

What I claim is—

The design for a frame for a cork-extractor; substantially as shown and described.

MICHAEL REDLINGER.
